LUBRICATING MEANS FOR SEWING-MACHINES.

1,217,976.

Specification of Letters Patent.

Patented Mar. 6, 1917.

Application filed May 19, 1915. Serial No. 29,231.

To all whom it may concern:

Be it known that I, JOSEPH M. MERROW, a citizen of the United States, residing in the city of Hartford, county of Hartford, State of Connecticut, have invented certain new and useful Improvements in Lubricating Means for Sewing-Machines; and I do declare the following to be a full, clear, and exact description of the same, reference being had to the accompanying drawings, forming a part of this specification, and to the characters of reference thereon.

This invention relates to lubricating means for sewing machines. Certain machines of this class are characterized by looper mechanism, of which, as is well known in this art, extremely high speeds are required. In the operation of such machines, increased efficiency naturally obtains by supplying continuously, adequate lubrication, directly to the relatively movable surfaces which are subjected to the greatest amount of frictional resistance. The provision of novel devices for carrying into effect this desideratum is one object of the present invention.

A design typical of the Merrow overseaming machine such as that illustrated in application for U. S. patent Serial No. 876,917, filed December 12, 1914, includes in its make-up a removable frame cap upon which is movably mounted looper mechanism such as that of which mention has been made above. It is a further object of the present invention to make provision in said frame cap for a lubricant reservoir with ducts and leaders associated therewith in such a manner that said frame cap together with the looper mechanism and its complete lubricating system may be assembled independently of the rest of the machine, and removed from the machine as an entirety to permit inspection and adjustment of the parts sustained thereby.

Other objects of the invention will hereinafter appear.

To clearly illustrate one form of embodiment of the invention the accompanying drawings are provided in which—

Figure 1 is a front view in elevation of a Merrow overseaming machine equipped with the devices which comprise the present improvements.

Fig. 2 is an inner face view of a remov-

able frame cap of the machine shown in Fig. 1.

Fig. 3 is a sectional view on line 3—3 of Fig. 2.

Fig. 4 is a detail view in perspective hereinabove more fully described, and

Fig. 5 is a sectional detail view.

Similar characters of reference designate corresponding parts throughout the several views of the drawings, which it will be noted are drawn to different scales.

Referring to said drawings the numeral 2 designates the frame of the machine, 3 the head, 4 the presserfoot and 5 the needle plate or work plate. An eye pointed needle 6, operable to move in a path extending above and below the needle plate 5, cooperates with the loopers 7 and 8 which are operatively supported on the frame cap 9, all as will hereinafter be more fully described. Said frame cap 9, which is secured to the machine frame at top and bottom by the screws 10, forms for an opening or cavity 11 in the machine frame, a closure or cover plate. Cam cylinders 12 and 13 housed within the cavity 11 are secured respectively to the shafts 14 and 15, the former shaft extending through to the rear of the machine frame where it is provided with a combined hand wheel and driving pulley 16. Intermeshing gears 17 and 18 are associated with the respective cam cylinders 12 and 13 so that when the pulley 16 is rotated the shafts 14 and 15 will together with said cam cylinders rotate in unison.

The function of these cam cylinders is to actuate the loopers 7 and 8 and a driving relation between the cylinders and said loopers may be established in a manner which will now be described. The lower cam cylinder 12, is provided with two cam grooves 19 and 20 while the upper cam cylinder 13 is provided with a cam groove 21. Extending respectively from oppositely disposed arms 22 and 23 of a carrier 24 for upper looper 7, into the respective cam grooves 19 and 21, are studs 25 and 26 provided with anti-friction rolls 27 and 28 respectively. Similarly a driving relation between lower looper 8 and cam cylinder 12 involves the carrier 29 from which extends into groove 20 of cam cylinder 12, a stud 30 provided with an anti-friction roll 31. By virtue of these driving connections the loopers 7 and

8 may be suitably moved in a manner well known to those familiar with this art, to coöperate with each other and with the needle 6, the latter being driven in any convenient way as from the shaft 15, through the parts indicated in a general way by 32.

The peculiar motion imparted to the looper carrier 24 by the correlated cam grooves 19 and 21 is accommodated preferably by providing a movable support for said carrier. This support may vary as to character, as shown, it comprises a slide or block 33 mounted for reciprocatory movement on the inner face of the frame cap 9 between guides 34 and 35, the latter guide being movable to take-up wear and backed up by an adjusting wedge 36 which bears against the shoulder 37 of said frame cap 9. In addition to the bodily movement of looper carrier 24 permitted by the slide 33 provision is also made for an oscillatory movement thereof, involving a pivotal connection comprising, as shown, a trunnion 38, projecting from said carrier 24, intermediate the oppositely disposed arms thereof, and journaled in said block 33. In order to retain the carrier 24 in its proper pivotal relation to the supporting block 33 and to provide additional support for said carrier, a guide bar 39 is mounted on the frame cap with a bearing surface 40 effectively positioned for the purposes stated. Said guide bar is provided at one end with an offset foot 41 countersunk to receive a screw 42 tapped into the frame cap, while at its opposite end said bar has a foot block 43 extending between the guides 34 and 35, which block is bored to receive a screw 43' countersunk in the front or outer face of the frame cap, and tapped into the bar proper.

The movement required of the lower looper 8 is an oscillatory one, by reason of which the looper carrier 29 may have a simple pivotal support. Such a support is provided in the taper stud 44 which is tapped into the frame cap and furnished with a securing nut 45.

The embodiment of the present invention within and applied to the devices hereinabove generally described will now be pointed out and explained.

In the upper part of the frame cap 9 which is somewhat enlarged for the purpose is provided a lubricant reservoir comprising in the present case a pair of drilled holes 46 and 47 plugged at the entering ends thereof and connected by a duct or ducts as 48. Below the reservoir proper are provided two packing cavities as 49 and 50 connected with the reservoir respectively by ducts as 51 and 52. The packing cavity 49, formed in the frame cap 9 is plugged at the entering end, and provided with a delivery duct 53 leading to the inclined face 54 of a fin or plate 55 suitably secured to the frame

cap. The packing cavity 50 is formed in the guide bar 39 and is provided with a delivery duct 56 leading to the inclined face 57 of a fin or plate 58 suitably secured to said guide bar.

It will be noted that a part of the duct 52 comprises a hole drilled through from the front face of the frame cap, said hole extending through the foot block 43, and into the bar 39 to the packing cavity 50. The outer end of the hole is plugged by the screw 52'. As will have been inferred the packing cavities 49 and 50 are filled with some material as felt to retard the flow of lubricant therethrough. By varying the density of such packing material the flow of lubricant may be regulated to any rate desirable.

Referring to Fig. 2 it will be noted that the fin 55 has a depending point 60 adjacent to the path traversed by the looper carrier arm 23 which supports the stud 26 and roll 28. In the face of arm 23 opposite the abutting end of roll 28 are formed the pockets 61 and 62 which open laterally on the opposite sides respectively of a portion 63 which may be termed a deflector, of arm 23 which is of sufficient extent to just clear the point 60 as said arm 23 moves in its reciprocatory path. Lubricant passing onto the fin 55 collects at the point 60 so that a quantity thereof is alternately wiped into the pockets 61 and 62 by the opposed edges of the deflector 63 as it passes back and forth, whereby an ample supply of lubricant is maintained advantageously available at all times for the roll 28 (see Fig. 4). The depending part of fin 58 is divided into two points 64 and 65 which extend into adjacency to the respective paths of the rolls 27 and 31. Adjacent downwardly diverging edges of the fin 58, merge beneath the duct 56 so that lubricant passing from the latter will divide and collect on both of said points 64 and 65. The looper carrier 29 supporting stud 30 and roll 31, (see Fig. 3) is notched as at 66 to receive lubricant therein from the fin point 65 as said point is passed by the carrier in the reciprocatory movement of the latter. In a similar way the arm 22 of looper carrier 24 is notched as at 67 to receive lubricant from the point 64.

In the front face of the frame cap 9 and communicating with the reservoir is a tapped hole, 68 countersunk to receive the head 69 of a threaded bushing 70. Said bushing has a sight opening 71 and is countersunk from its inner end to receive the transparent disk 72, washer 73 and spacing ring 74. The latter is adapted to bear against a second washer 75 at the bottom of the tapped hole thus providing for tight joints between the several parts mentioned when the bushing is screwed into place, to provide means whereby an operator can readily ascertain if the reservoir contains

lubricant. Ports through which lubricant may be introduced into the reservoir are designated by 76.

While specific terms have been employed in the foregoing description of the particular embodiment of the invention disclosed in the drawings it will be understood that the invention is not limited thereto; as other forms of its embodiment may be produced within the scope of the appended claims.

What I claim is:—

1. In a sewing machine including looper mechanism, and in combination therewith a lubricator for said looper mechanism comprising a lubricant reservoir located above said looper mechanism, fins having depending points adjacent respectively to paths traversed by certain parts of the looper mechanism and ducts leading from said lubricant reservoir to said fins.

2. In a sewing machine including looper mechanism, and in combination a support for said looper mechanism comprising a frame cap having a lubricant reservoir, fins secured to said frame cap having depending points adjacent respectively to paths traversed by certain parts of the looper mechanism and ducts leading from said lubricant reservoir to said fins.

3. In a sewing machine the combination with a frame cap having a lubricant reservoir, of looper carriers movably mounted on said frame cap, devices on said carriers whereby they may be actuated, fins secured to the frame cap and having depending points adjacent respectively to paths traversed by said devices on the looper carriers and ducts leading from the lubricant reservoir to said fins.

4. In a sewing machine in combination, a looper, a support, a carrier for the looper movable on said support, means including a roller supported by the carrier whereby the latter may be actuated to move in a predetermined path, means extending adjacent to said path for conveying lubricant to a point therein, and means on the carrier for directing the lubricant from said point into communication with bearing surfaces of the roller.

5. In a sewing machine in combination, a looper, a support, a carrier for the looper movable on said support, means including a projection on the carrier whereby the latter may be actuated, a lubricant reservoir, and a conveyer or fin connected to said reservoir by a duct and depending to a point approached by the projection on the carrier whereby said projection will be supplied with lubricant.

6. In a sewing machine in combination, a looper, a support, a carrier for the looper movable on said support, means including a projection on the carrier whereby the latter may be actuated, a lubricant reser-

voir, a conveyer or fin connected by a duct with the reservoir and adapted to transfer lubricant from a depending part thereof to the projection on the carrier at a point approached by the latter and means for regulating the flow of lubricant through said duct.

7. In a sewing machine in combination, a pair of loopers, a support, a movable member carried by the support, a carrier for one of the loopers movably mounted on the movable member, a carrier for the other looper movably mounted on the support means including projections on the respective carriers whereby the latter may be actuated, a lubricant reservoir and a conveyer or fin having parts depending to points approached respectively by the projections of the carriers and adapted to transfer thereto lubricant delivered through a duct connecting said conveyer with the reservoir.

8. In a sewing machine in combination, a pair of loopers, a support, a movable member carried by the support, a carrier for one of the loopers movably mounted on the movable member, a carrier for the other looper movably mounted on the support, a guide bar for the first mentioned carrier secured to the support, means including projections on the respective carriers whereby the latter may be actuated, a lubricant reservoir, and a conveyer or fin secured to the guide bar and connected with the reservoir by a duct partially in the guide bar, said conveyer having parts depending to points approached respectively by the projections on the carriers and adapted to transfer lubricant thereto.

9. In a sewing machine in combination, a looper, a support, a carrier for the looper movably mounted on the support, a movable element for actuating the looper carrier, a connection between said movable element and the carrier whereby the latter may be actuated, a deflector on the carrier flanked on opposite sides by pockets communicating with said connection and a conveyer for delivering lubricant to a point in a path traversed by said deflector.

10. In a sewing machine in combination, a looper, a support, a carrier for the looper movable on said support, a cam cylinder provided with a groove, a device associated with the carrier adapted to engage said groove and to be actuated thereby, a lubricant reservoir, and a conveyer or fin connected by ducts to said reservoir, said conveyers depending to a point approached by the device associated with the carrier whereby said device will be supplied with lubricant.

11. In a sewing machine in combination, a looper, a support, a carrier for the looper movable on said support, a pair of grooved

cam cylinders, separate devices associated with the carrier and engageable by respective grooves of the two cam cylinders, a lubricant reservoir, and conveyers or fins 5 connected by ducts to the reservoir, said conveyers depending to points approached by respective devices associated with the

carrier whereby said devices will be supplied with lubricant.

JOSEPH M. MERROW.
